SOUND RECORDING SYSTEM

Russell M. Otis, Alhambra, Calif.

Original application July 17, 1929, Serial No. 378,994. Divided and this application December 23, 1930, Serial No. 504,266

19 Claims. (Cl. 179—100.3)

5 My invention relates to a novel system for indicating or recording various phenomena, and more particularly to a novel apparatus for recording sounds or other phenomena on a motion-picture film or other photo-sensitive element, the present application being a division of my co-pending application entitled "Process of and apparatus for photographically recording sounds," filed July 17, 1929, Serial No. 378,994.

10 As disclosed in that application, it is known that an exposure of a photo-sensitive element can be obtained by positioning electrodes on opposite sides thereof and impressing a momentary high potential across these electrodes. The resulting exposure, when subjected to the usual developing methods, appears in the form of a large number of lines extending radially from the area of contact between the electrode and the photo-sensitive element. Such figures are known in the art as Lichtenberg figures.

20 As further set forth in my co-pending application, I have found that it is possible to form an exposure in the area between the electrodes if the voltage gradient is sufficiently high, and by confining the discharge it is possible to expose a portion of the photo-sensitive element in the form of a minute line which is preferably equal to or less than $\frac{1}{1000}$ of an inch in width, and of a length equal to or less than the space on the motion-picture film allotted to a sound track. 25 By suitably modulating the potential impressed across the electrodes as a function of the sound or other phenomena to be recorded, and by moving the photo-sensitive element between these electrodes, I have found it possible to accurately record the phenomena on the film, the developed film showing a plurality of "lines" extending across the sound track, each "line" being of equal intensity across this sound track, but succeeding "lines" varying in density with respect to each other. The result is a sound track which appears quite similar to those sound tracks at present known in the art as the variable density type.

30 The present invention is directed to a system of recording by the use of a modified form of this type of discharge, the resulting sound record containing a plurality of "lines", each successive "line" being of different density, and each "line" itself having a density which varies across the sound track. Such a record is a combination of the so-called variable density and variable area records at present well known in the motion-picture art. This type of record is very desirable, and gives a very accurate reproduction when used in conventional reproducing sys-

tems or in systems especially designed therefor.

It is an important object of the present invention to provide a photo-sensitive element, such as a motion-picture film, which includes an area or track containing a plurality of such "lines", successive "lines" being of different density, and each "line" being of varying density throughout its length.

35 A further object of the invention lies in the provision of a novel apparatus for forming such a sound track, and my experiments have shown that several methods of obtaining such a record are possible. In one of these methods, one or both of the electrodes are formed of a high-resistance material such as silicon, and the current is conducted therethrough in a path which extends substantially parallel to the surface of the light-sensitive element. A voltage drop is thus set up, so that the voltage between the electrodes at any point is equal to the applied voltage 40 across the electrodes less the voltage drop in the electrodes taking place in that portion of the electrode lying to one side of the section under consideration. The discharge thus set up between the electrodes is of non-uniform intensity and the resulting exposure is a function of the intensity of this discharge.

45 It is an object of this invention to provide a method and apparatus of recording wherein at least one of the electrodes is formed of a material having a relatively high resistance, whereby the current flowing therethrough sets up a voltage drop, the magnitude of this drop depending upon the distance the current has travelled.

50 Another system whereby such a desirable sound record may be formed includes the formation of electrodes in such a manner that the gap formed therebetween is tapered. The photo-sensitive element is positioned in this gap, and due to the taper thereof the gradient set up therein will be non-uniform throughout the length of the gap, and the discharge will be much more intense in the narrower portion of the gap than in the wider portion thereof.

55 It is an object of this invention to provide a recording system wherein a relatively long and narrow discharge is set up, this discharge being of non-uniform intensity throughout its length.

60 A further object of the invention is to provide such a non-uniform discharge, and to modulate this discharge with the phenomena to be recorded.

65 A further object of the invention is to provide such a tapered gap between a pair of electrodes so arranged that that portion of the tapered

gap not occupied by the photo-sensitive element is substantially filled with a suitable dielectric.

My invention also includes the combined use of a high-resistance electrode structure and a 5 tapered gap, as will be set forth hereinafter. Various modifications of exposure may be obtained by such a combination, the variation in discharge due to the gap either being additive or subtractive with relation to the variation in discharge due to the resistance of the electrode 10 structure.

It is an object of this invention to provide a recording system combining a high-resistance electrode with a tapered gap in which the photo-sensitive element is positioned.

Other systems whereby such a desirable sound record may be produced will be apparent from the disclosure hereinafter.

Further objects of the invention lie in a novel 20 electrode structure wherein fringing of the discharge is prevented, and wherein the resultant exposure may be limited in shape to a desired area.

Other objects and advantages of the invention 25 will be made evident hereinafter.

Referring to the drawings, in which I have shown several possible systems producing my new type of sound record,—

Fig. 1 illustrates one type of high-resistance 30 electrode structure in combination with a typical modulating circuit.

Figs. 2 and 3 illustrate other types of high-resistance electrode structures, Fig. 2 being taken along the line 2—2 of Fig. 1.

35 Figs. 4 to 7 illustrate varying-gap electrode structures.

Figs. 8 and 9 illustrate combinations of the varying-gap and high-resistance electrode structures.

40 Fig. 10 diagrammatically illustrates a sound track, greatly magnified, made by the electrodes of my invention.

The general appearance of the invention may 45 be best understood by reference to Fig. 1, which illustrates one form of the electrode structure in combination with one type of modulator circuit more particularly set forth in my co-pending application supra. The particular circuit shown in Fig. 1 is not a part of this invention, and it 50 should be clearly understood that numerous other modulating circuits well known in the art might be used. Essentially, however, the circuit shown in Fig. 1 comprises an oscillator tube 15 which sets up a high-frequency oscillation which 55 is modulated by a modulator tube 16 in response to the variations in the phenomena to be recorded. When used for recording sound, a microphone 17 is coupled with the modulator tube 16 in such a manner that the high-frequency 60 oscillations are modulated by the sounds picked up by this microphone in any well-known manner. This modulated potential is impressed across a pair of electrodes, this being accomplished in the circuits shown in Fig. 1 including 65 an auto-transformer 20 having output conductors 21 and 22, the entire modulating system being hereinafter termed a current supply means 25.

Two electrode structures are illustrated in Fig. 70 1, termed respectively primary and secondary electrode structures 27 and 28. These structures are spaced a distance apart substantially equal to the thickness of a photo-sensitive element on which a record is to be impressed, this 75 photo-sensitive element being illustrated and

hereinafter referred to as comprising a motion-picture film 29 having a celluloid backing 30 and an emulsion surface 31 thereon, and being provided with sprocket holes 32 in the usual manner. That portion of the motion-picture film lying 5 between the lines A—A and B—B comprises the sound track 33 on which the recording takes place, the pictorial image being recorded to the left of the sound track as viewed in Fig. 1.

In this form of the invention the primary electrode structure 27 comprises a pair of blocks 35 and 36 which support a blade or knife-edge electrode 38. In practice I prefer to form the blocks 35 and 36 of an insulating material and to utilize for the electrode 38 either an extremely thin foil of a relatively high-resistance material or some other thin layer or deposit of such a material. This high-resistance material, however, has a much higher conductivity than the blocks 35 and 36. These blocks thus support 20 the electrode 38, and the whole electrode structure is accurately ground to provide a contacting surface 39 lying in a single plane and including a knife-edge 40 of the electrode 38. This is preferably done after the blocks and electrode 25 are suitably clamped or cemented together, so that the contacting surface 39 presents a smooth, flat surface as set forth in my co-pending application.

The thickness of the electrode 38 is preferably 30 less than $\frac{1}{1000}$ of an inch, this being necessary in order to accurately record on a conventional motion-picture film moving at the usual speed all of the overtones in the sound to be recorded. In my co-pending application the material forming 35 this electrode is a metal having a very high 40 conductivity, but in the instant application it is desirable to use a material having a relatively high electrical resistance. Such a material is silicon, which may, by carefully working, and in some cases by a special process, be formed into a foil less than $\frac{1}{1000}$ of an inch in thickness. Certain 45 metals also have a high enough resistance to be successfully used in forming the electrode 38, and certain stones or minerals having a high 50 resistance can be used, where these are easily 55 polished and especially in the forms to be later described. So also certain alloys are useful in this capacity, and it is entirely possible to form a very thin coating on one or both of the blocks 50 by spraying thereon such high-resistance materials in molten or molecular state, thereby building up a coating of the required thickness. It is 55 also possible to apply such a coating by other means, and a satisfactory electrode can be obtained by mixing a powdered conducting material such as lampblack with certain other materials such as, for instance, sodium silicate. Certain 60 other compounds formed of carbon and "bakelite" can also be used in some instances. 65 The particular material utilized depends upon a number of factors, including the workability and the desired resistance. In certain instances it is desirable to use the mixtures or alloys, for 65 obviously it is possible to secure an electrode of any desired resistance, though in other instances it is equally effective to utilize certain of the other materials and design the current supply means so that the desired effect is obtained. Certain other factors which must be taken into 70 account when determining the resistance or setting of the current supply means will be more clearly set forth hereinafter.

The secondary electrode structure 28 is similarly constructed, utilizing blocks 42 and 43 as a 75

supporting structure for an electrode 44. In the form shown in Figs. 1 and 2, the electrode 44 lies in the same plane as the electrode 38, and the thickness thereof preferably does not exceed 5 $\frac{1}{4000}$ of an inch. In this form of the invention, the electrode 44 may be either an electrode formed of a high-resistance material, such as outlined above, or an electrode formed of a material having a high electrical conductivity. Both the electrodes 38 and 44 are preferably provided with 10 rounded edges adjacent the photo-sensitive element 29, as best shown in Fig. 1, to prevent concentration of the discharge there adjacent, these electrodes being in contact with the photo-sensitive elements over a distance equal to or slightly 15 greater than the width of the sound track represented as lying between the lines A—A and B—B.

To secure the desired effect when utilizing a high-resistance electrode, it is necessary that the 20 current flow through this high-resistance electrode in such a manner that a voltage drop occurs across that portion thereof which is in close proximity to the photo-sensitive element 29. It is thus preferable that the current pass through 25 this high-resistance electrode in a direction substantially parallel to the surface of the photo-sensitive element, and thus I have illustrated terminal portions 48 and 49 on the electrode 38 between which terminal portions the current 30 flows, the former terminal portion being connected to the conductor 21. The conductor portion 49 is connected to a conductor 50 which is in turn connected to a terminal portion 51 of the electrode 44, there being another terminal portion 35 52 connected to the conductor 22.

Considering, for instance, that the electrode 38 is of high-resistance material, and the electrode 44 is formed of a material having a relatively high conductivity such, for instance, as 40 platinum, it will be apparent that the potential between the electrodes at the section A—A will be substantially equal to the potential of the current supply means at any instant. However, the potential between the electrodes at the section 45 C—C will be much less due to the voltage drop taking place in the electrode 38 when the current flows between the terminal portions 48 and 49. In fact, the voltage between the electrodes at the section C—C will be substantially 50 equal to the voltage of the current supply means at any instant, less the voltage drop set up by the current in passing through that portion of the electrode 38 to the left of the section C—C. This voltage drop is proportional to the product 55 of the current and the resistance of that portion to the left of the section C—C. It will thus be apparent that the voltage between the electrodes at the section A—A is much greater than between these electrodes at the section C—C, 60 and that both of these voltages are higher than the voltage between the electrodes at the section B—B.

It is thus apparent that the discharge set up 65 between the electrodes will be non-uniform between the sections A—A and B—B; in other words, this discharge will progressively decrease from one boundary of the sound track to the other. By so controlling the current supply means with respect to the resistance of the electrode 38 that the voltage between the sections A—A is sufficient to expose the film, while the voltage at the section B—B is insufficient to expose the film, or at least exposes this film to a lesser degree at the latter section, the result is 70 that a line will be formed on the photo-sensitive 75

element 29 which will be apparent after development, this line being much more dense adjacent that boundary of the sound track indicated by the section A—A than at any other section along the length of this line. In fact, the exposure will 5 gradually fade off. Such a line would appear similar to the "line" 53 of Fig. 10, the boundaries of the sound track being represented by the lines A—A and B—B. Necessarily, Fig. 10 is diagrammatic inasmuch as it is impossible to exactly 10 represent the fading off. This figure viewed at a distance does, however, give the general impression of the fading which takes place.

If, now, the potential between the conductors 21 and 22 is modulated, for instance, by the 15 sounds to be recorded, the result is that the discharge at a given section is correspondingly made greater or smaller. Thus, if the film 29 is moved relative to the electrode structures, the result is a series of "lines" indicated in Fig. 10, each successive "line" being of different density than the adjacent "lines". The term "line" is not entirely 20 correct, especially when referring to Fig. 10 wherein the length of the sound track has been greatly distorted so that the fading can be represented. In reality, the spaces between the "lines" of Fig. 10 do not appear completely unexposed to the extent represented, as will be apparent 25 to those skilled in the art.

If the electrode 44 is also made of high-resistance material, a voltage drop will also take place therein in the same manner as the voltage drop which takes place in the electrode 38.

In any event the blocks positioned adjacent the knife-edge electrode prevent a spreading of 35 the discharge along the surface of the photo-sensitive element. Such a discharge would inevitably take place if some means were not utilized for preventing it, and the resulting exposure on the sound track would be ineffective to record 40 sounds if a moving-picture film is utilized and moved at the usual rate. In the recording of sound on a motion-picture film it is thus important that this fringing be eliminated.

It should not be understood, however, that I 45 am limited to two knife-edge electrodes. Thus, in Fig. 3 I have illustrated a knife-edge electrode 57 above the film, and have illustrated a relatively massive electrode 58 below this film, this latter electrode being in the form of a plate or 50 bar, for instance. Such a system is especially advantageous when the emulsion side of the film moves in contact with the knife-edge, and it has been found that the spreading effect when utilizing a relatively massive electrode such as the 55 electrode 58 is not materially greater than when using a knife-edge electrode such as the electrode 44. In the system shown in Fig. 3, the conductor 50 is shown as being connected to a terminal portion 59 of the electrode 58, the conductor 22 being connected to a terminal portion 60 thereof. In this form of the invention either the electrode 57 or the electrode 58, or both, may be formed of high-resistance material, and the 65 result will be similar to the results previously described. If the electrode 58 is formed of a high-resistance material, such as silicon or suitably polished stones, it is sometimes desirable to utilize separate low-resistance electrodes for sending current through the high-resistance electrode 58. 70 This may be accomplished by utilizing a plate electrode on opposite ends of the electrode 58, these plate electrodes being in pressure contact therewith.

As described in my co-pending application, it 75

is also possible to substitute a roller for the electrode 58, or a roller incorporated in a sprocket. Regardless of the electrode utilized, it is possible to form this of material having a relatively high resistance so that the desirable effect is obtained.

A second system whereby the desirable type of record shown in Fig. 10 may be obtained is to use two electrodes so disposed as to form a tapering gap therebetween and in which the film is positioned. Thus, in Fig. 4 I have illustrated blocks 80 and 81 forming a supporting structure for a primary knife-edge electrode 82. The lower edge of this electrode is not, however, in surface contact with the photo-sensitive element 29 over the total width of the sound track represented between the lines A—A and B—B. Instead, however, substantial contact between the electrode and the photo-sensitive element takes place at the section B—B, while a gap exists between the electrode and the surface of the photo-sensitive element at the section A—A. A secondary electrode 84 is positioned below the photo-sensitive element and in surface contact therewith, this secondary electrode being in the form of a bar or plate. In this embodiment of the invention both the electrodes 82 and 84 are formed of a metal having a high electrical conductivity, one of these electrodes being connected to the conductor 21 and the other to the conductor 22 of the current supply means 25.

There is thus set up between the electrodes 82 and 84 a discharge of non-uniform intensity, this discharge being more intense at the section B—B than at the section A—A due to the difference in spacing between the electrodes. The result is that the discharge exposes the film to a greater degree at the section B—B than at the section A—A, thus forming a "line" of variable density on the photo-sensitive element. By modulating the potential and moving the film therebetween, the result is a series of exposures along the sound track, each exposure varying in intensity across the sound track and succeeding exposures varying in intensity along the sound track.

In Fig. 5 I have shown a system utilizing two electrode structures having knife-edge electrodes, one of these electrodes being designated a primary electrode 88 and providing an angled surface 89 and the other of these electrodes being designated a secondary electrode 90 and providing a contacting surface 91.

Similarly, in Fig. 6 I have shown a pair of electrode structures in which both electrodes are in the form of knife-edges, each being provided with an angled surface whereby the distance between the electrodes increases even greater per unit of distance across the sound track.

Fig. 7, however, shows the system most easily constructed, one electrode structure being formed with a knife-edged primary electrode 100, which is in surface contact with the film across the sound track, a secondary electrode being indicated by the numeral 101 and being in the form of a tapered block or rod having an angled surface 102 spaced varying distances from the surface of the film so as to cooperate with the electrode 100 in providing a varying gap across the sound track. In this form of the invention, that portion of the gap which is not required for the movement of the film is filled with a dielectric indicated by the numeral 103, so that the film moves in contact with this dielectric and is thereby held in correct relationship relative to the electrode 100. In some instances it is advisable

to extend the dielectric around the edges of the electrode 101, as shown in Fig. 7.

Combinations of the high-resistance electrode system and tapering gap system are also possible. Thus, in Fig. 8 I have illustrated a knife-edge electrode 110 of high-resistance material in combination with a block electrode 111 having an angled surface 112. As shown in Fig. 8, the conductor 21 is connected to that portion of the electrode 110 which lies the closest to the electrode 111.

The effect of the high-resistance electrode is thus additive relative to the effect of the tapering gap, for not only is the voltage of the section B—B lower than at the section A—A due to the voltage drop across the electrode 110, but the voltage gradient is also lower because of the added spacing between the electrodes at the section B—B. Nor is it necessary to use an angled electrode of low resistance and a knife-edge electrode of high-resistance material, for both may be of high-resistance material or the angled electrode may be alone of high-resistance material with the knife-edge electrode of low-resistance material.

It is sometimes desired to connect these electrodes in subtractive relation, in which case the electrodes may be connected, as shown in Fig. 9, the upper electrode 110 being the high resistance electrode, and the electrode 111 being the low-resistance electrode.

The voltage across the electrodes at the section A—A will be equal to the instantaneous voltage of the current supply means 25, but the discharge therebeyond will be lessened due to the added spacing of these electrodes at this section. This spacing of the electrodes is much smaller at the section B—B, thus tending to increase the discharge thereat. On the other hand, the voltage between the electrodes at the section B—B is less than at the section A—A considering the voltage drop in the electrode 110. Whichever effect is the greater will control the varying density of the resulting image.

While I have shown the angled surfaces of the electrodes as being disposed in a straight line, it should be understood that this is not necessary to the invention. These angled surfaces may be formed on a suitable curve whereby the voltage gradient between the electrodes at any section of the sound track is dependent on this curve. This is especially desirable inasmuch as it allows compensation for other errors which might occur in this system due to the use of a particular apparatus. So also, the curve of this angled surface may be designed in conjunction with the shape of the H and D curve representing the relationship between density and exposure with a given developer and a particular film utilized. Thus, if the operator is working on a curved portion of the H and D curve distortion might be introduced into the sound record due to this curve, but if the shape of the angled surface was so designed with relation to the particular portion of this H and D curve utilized, this distortion can be compensated for.

It should thus be apparent that I am not limited to a tapering gap in which the distance between the electrodes increases uniformly across the sound track. Furthermore, while I have shown the knife-edge electrode as extending perpendicularly across the sound track, this is not essential to the invention, it only being necessary that this electrode extend transversely whether or not

such transverse extension is perpendicular. Finally, my system is novel in other capacities than in the recording of sound on a motion-picture film, and can be used with various other 5 photo-sensitive elements whether these are moving or stationary relative to the electrode structures.

I claim as my invention:

1. In a recording system for recording on a 10 photo-sensitive element, the combination of: a primary electrode positioned close to said photo-sensitive element and formed of a high-resistance material; a current source for sending a current through said primary electrode in a direction 15 across said photo-sensitive element whereby a voltage drop takes place across said primary electrode; and a secondary electrode means positioned on the opposite side of said photo-sensitive element from said electrode and electrically connected to said current source, said 20 current source developing sufficient potential to expose said photo-sensitive element.

2. A combination as defined in claim 1 in which 25 said primary electrode provides a pair of terminal means on opposite ends thereof, one of said terminal means being connected to one terminal of said current source, the other terminal of said current source being connected to said secondary electrode means, and including a conducting 30 means connecting said secondary electrode means and the remaining terminal means of said primary electrode.

3. In a recording system for recording phenomena on a moving photo-sensitive element the 35 combination of: primary and secondary electrodes positioned on opposite sides of said moving photo-sensitive element, at least one of said electrodes being in the form of a knife-edge extending transversely relative to the direction of 40 movement of said photo-sensitive element, said primary electrode being formed of high-resistance material and providing a pair of terminal means spaced from each other in the direction 45 of the length of said knife-edge; means for impressing a high potential across said electrodes and varying in response to the variations of the 50 phenomena to be recorded, said means including a conductor connected to one terminal means of said primary electrode, and another conductor connected to said secondary electrode; and a conducting means connecting said secondary electrode and the other terminal means of said primary electrode whereby the voltage gradient between 55 electrodes is non-uniform along said knife-edge electrode at any instant.

4. In a system for recording on a photo-sensitive element, the combination of: primary and secondary electrodes positioned on opposite sides of said photo-sensitive element and spaced from each other to form a tapering gap; means for establishing a potential difference between said electrodes of sufficient magnitude to expose that portion of said photo-sensitive element lying therebetween, but of insufficient magnitude to puncture said photo-sensitive element; and means for confining said discharge to prevent spreading thereof.

5. A combination as defined in claim 4 including 70 a dielectric medium filling that portion of said tapering gap not occupied by said photo-sensitive element.

6. A combination as defined in claim 4 in which at least one of said electrodes is in the form of a 75 knife-edge, and in which said means for confining

said discharge comprises means adjacent said knife-edge and contacted by said photo-sensitive element.

7. A combination as defined in claim 4 in which one of said electrodes contacts said photo-sensitive element throughout the length of this electrode, the other of said electrodes being spaced unequal distances from said light-sensitive element to form said tapering gap. 5

8. In a system for recording on a photo-sensitive element, the combination of: a primary electrode in the form of a thin element providing an edge in surface contact with said photo-sensitive element throughout the length of said electrode; a secondary electrode on the opposite side 15 of said photo-sensitive element from said primary electrode and providing an inclined surface spaced varying distances from said photo-sensitive element and oppositely disposed relative to said edge of said primary electrode; and means 20 for impressing a potential across said electrodes sufficient to expose that portion of said photo-sensitive element lying therebetween, but of insufficient magnitude to puncture said photo-sensitive element. 25

9. In a system for recording on a photo-sensitive element, the combination of: an electrode on one side of said photo-sensitive element; an angled electrode on the other side of said photo-sensitive element and spaced from said first- 30 mentioned electrode to form a tapering gap at least one of said electrodes being formed of a material having a relatively high electrical resistance; and current supply means impressing a potential difference between said electrodes 35 whereby current flows through said electrode of high-resistance material in a direction across said photo-sensitive element.

10. An electrode structure comprising: an electrical conductor providing a discharge edge; 40 and a tapered solid dielectric member adjacent said discharge edge and providing a contacting surface extending at an angle to said discharge edge, whereby said discharge edge is closer to said contacting surface at one end than at an- 45 other end.

11. An electrode structure comprising: a member formed of high-resistance material providing a discharge edge; and two terminal means on said member and spaced from each other in the direction of said discharge edge whereby a current flowing therebetween moves substantially in the direction of said discharge edge and sets 50 up a voltage drop therealong.

12. An electrode structure comprising: a mem- 55 ber formed of silicon and providing a discharge edge; and two terminal means on said member and spaced from each other in the direction of said discharge edge whereby a current flowing therebetween moves substantially in the direction 60 of said discharge edge and sets up a voltage drop therealong.

13. An electrode structure comprising: a pair of electrodes spaced from each other to define a gap in which a discharge may be established, one 65 of said electrodes being formed of a relatively high-resistance material; means for forcing an electric current through said one of said electrodes which is formed of high-resistance material and in a direction along said other of said electrodes 70 whereby a voltage drop takes place in said high-resistance electrode to decrease the potential existing between said electrodes along said gap, thereby setting up an electric discharge of non-uniform intensity in said gap. 75

14. In combination in a system for recording on a photo-sensitive element: means for establishing a long and narrow discharge through said photo-sensitive element which discharge is of much greater intensity at one portion of its length than at another portion of its length and is of intermediate intensity between said portions, said means including a knife-edge electrode on one side of said photo-sensitive element, an auxiliary electrode means on the opposite side of said photo-sensitive element, and a means for establishing a potential difference between said electrodes to establish a discharge sufficient to expose said photo-sensitive element.
15. 15. A combination as defined in claim 14 including means for confining said discharge to an area not substantially wider than said knife-edge.
16. In a recording system for recording phenomena on a moving photo-sensitive element, the combination of: means including electrodes on opposite sides of said moving photo-sensitive element for setting up a lineal discharge between said electrodes and of non-uniform intensity in the direction of its length, the intensity gradually varying from one portion of said lineal discharge to another portion thereof; and means for varying the intensity in all portions of said lineal discharge in response to the variations of the phenomena to be recorded whereby a varying intensity discharge is set up between said electrodes sufficient to expose said photo-sensitive element therebetween but insufficient to puncture said photo-sensitive element.
17. In combination with a photo-sensitive element: a primary electrode formed of a high resistance material and providing a discharge edge positioned adjacent said photo-sensitive element; means including a current source for

sending current through said primary electrode in a direction along said discharge edge whereby a voltage drop takes place along said discharge edge; and a secondary electrode connected to said current source and cooperating with said discharge edge of said primary electrode in bounding a discharge space in which said current source sets up a discharge which exposes said photo-sensitive element, said discharge being of non-uniform intensity along the length thereof due to the voltage drop along said discharge edge. 5

18. A method of recording on a photo-sensitive element, which method includes the steps of: establishing a long and narrow discharge through said photo-sensitive element and of much greater intensity at one portion of its length than at another portion of its length and of intermediate intensity between these portions, said discharge at said one portion of the length of said discharge being sufficient to expose said photo-sensitive element, and said discharge of said other portion of said discharge being of insufficient intensity to materially expose said photo-sensitive element, said intermediate intensity between said portions exposing said photo-sensitive element in decreasing amounts from said one portion toward said other portion. 15 20 25

19. A method as defined in claim 18 including the additional steps of: moving said photo-sensitive element transversely with respect to said discharge; and varying the intensity throughout the length of said discharge in response to the variations in the phenomena to be recorded whereby successive portions of said photo-sensitive element are exposed over varying fractions of the length of said discharge. 30 35
